RATAN-SCRAPER.

1,079,056.

Specification of Letters Patent.

Patented Nov. 18, 1913.

Application filed August 23, 1912. Serial No. 716,615.

To all whom it may concern:

Be it known that I, HINRICH MEIER, workmaster, a subject of the German Emperor, residing at Oslebshausen, near Bremen, Germany, have invented a new and useful Improvement in Ratan-Scrapers, of which the following is a specification.

The object of this invention is to provide an improved ratan scraper and slicer which will produce clean work practically free from bark.

Machines for scraping and slicing ratan are known in which scraper-blades are arranged radially but these have the disadvantage that canes of various thicknesses cannot be worked indiscriminately without leaving unscraped ribs more or less in width on the core and thereby entail waste of material or at least a partly reduced selling price. In another type of machine for the aforesaid purpose, the scraper-blades are not radially disposed and only a single polygonal blade, or two blades in opposite positions, is or are provided so that the operation requires at least two passages of the cane through the machine by turning each cane axially through 90 degrees. Also with this arrangement of scrapers there remain usually four unscraped ribs on the cane which in thick canes present considerable loss when considering the manufacture in bulk.

The invention is based on a combination of the two separately known systems with a view of attaining the combined advantages without their inherent disadvantages.

This improved ratan scraper device contains in combination the radial arrangement of a plurality of blade-holders with group-wise incorporated slicers in form of polygonal cutters all mounted together in a holder providing radial adjustment. The more polygonal cutters are incorporated in a group with the scrapers in each holder the closer together will the scrapers attack the bark of the cane so that no intervening ribs of bark can possibly be left by any one group in the holder. Ribs can only be left in the interval between the several groups of cutters and scrapers so that the peripheral surface of the canes is more fully utilized. Further with the scraping devices referred to as the second known type it is only possible to scrape an even number of ratan strips, while with the present combined radial adjustable scraper and slicer any uneven number of

strips can be produced from single canes. The said improved device delivers the strips ready for use by a single passage of a cane, that is to say that no subsequent trimming operation is necessary.

An embodiment of the invention is shown by way of example in the drawings hereunto annexed, in which:

Figure 1, is a face view of the holder with the front cover removed; Fig. 2, is a section on line A—B—C of Fig. 1; Fig. 3, is a longitudinal section of one of the combined scrapers and slicers and Fig. 4, is a face view of same.

In the example shown in the drawings there are three scraper-slicers *a* having three polygonal cutters comprising head cutters *c* and side-cutters *d*. The latter serve as slicers, while the head cutters *c* act as scrapers. The strips pass through the polygonal openings *b*. Each tool *a* is mounted with its prismatic end portion *a*¹ in a rectangular groove in a guide block *f* and secured to the latter by a screw *g* which passes through a longitudinal slot *h* of the tool *a*. Each such tool *a* can be set along the slot *g* so as to suit the thickness of the strips to be produced, while the width of the same depends on the unmovable distance of the radial side cutters *d*. The blocks *f* (Fig. 1) are mounted on the carrier plate *i* between guides *j* so as to be radially movable, and their forward portion is cone-shaped toward the polygonal cutters, see Figs. 2 and 3. The scrapers are inclined in the opposite direction to the advancing canes.

The blocks *f* and the guide pieces *k* are surrounded by an annulus *m* (Fig. 1), which is formed with a triangular recess *o* opposite each tool *a*, the inclined surface *o*¹ of each recess pressing against the rear edge *f*¹ of each tool. When the annulus *m* is being turned in the direction of the arrow (Fig. 1) by means of a handle *m*¹, the tools are forced inward toward the center so as to suit various thicknesses of canes. The blocks *f* are kept in position by means of a cover *p* (Fig. 2) secured by means of screws *q* to the fixed guides *k*. At the outlet for the unused core of the cane and for the separate strips, there is provided a funnel *t*. The cane *r* to be treated is introduced at *s* (Fig. 2) while the unused core *w* and ready made strips *v* issue from the funnel *t*. The ribs left on the core *w* will be found to be ex-

ceedingly thin owing to the use of this improved combined device, and are hardly worth considering in comparison with the ribs left in the treatment with the ordinary machines. To enable the core *w* to be utilized for other purposes the thin adhering ribs can be readily scraped off by any suitable circular knife.

- I claim:
10. A ratan scraping and slicing tool-head consisting of radially movable scraper blocks, integral polygonal end cutters and side cut-

ters fast on said blocks, angular outer ends formed on said blocks, intervening guide pieces for the latter, a carrier plate for same, a turnable annulus surrounding said blocks and cutters, and triangular recesses providing an inclined bearing surface for the angular ends of the blocks, as and for the purpose described.

HINRICH MEIER.
